UNITED STATES PATENT OFFICE.

WILLIAM B. DENNIS, OF HAGERSTOWN, MARYLAND.

BRUSH.

1,111,955.

Specification of Letters Patent. Patented Sept. 29, 1914.

Application filed October 18, 1913. Serial No. 795,975.

To all whom it may concern:

Be it known that I, WILLIAM B. DENNIS, a citizen of the United States, residing at Hagerstown, in the county of Washington 5 and State of Maryland, have invented certain new and useful Improvements in Brushes, of which the following is a specification.

This invention relates to an improved 10 brush which is intended to be carried about in the pocket so that a hat or coat can be brushed in case they become dusty. It very often happens that a hat will fall upon the street where it will become dirty. It is then 15 necessary for the wearer to either use his coat sleeve or handkerchief to clean the hat. While this method will remove the dirt to a certain extent, it will not accomplish the object as well as if the person had a small 20 brush in his pocket.

One of the objects of this invention is to so construct the brush that it may be withdrawn from a case and held in an extended position, while being used.

25 Another object of the invention is to provide a brush which is limited in its outward movement from the case, thus preventing the brush from dropping out of the case while in use.

30 Another object of the invention is to provide the case with a removable end so that the end may be removed and the brush withdrawn from the case and a new one put in its place.

35 This invention is illustrated in the accompanying drawings wherein—

Figure 1 is a side elevation of the case in which the brush is mounted; Fig. 2 is a longitudinal sectional view through the case 40 with the brush shown in elevation; Fig. 3 is a longitudinal sectional view taken along the line 3—3 of Fig. 2 with the brush moved to the extended position; and Fig. 4 is a transverse sectional view taken along the 45 line 4—4 of Fig. 2.

The case 10 for this brush is open at each end and provided with removable caps 11 and 12. The brush which is indicated in general by the numeral 13 comprises the 50 head 14 which has the bristles 15 secured therein by means of the rivets 16. This

brush is inserted in the case through the open end which is normally closed by the cover 11 and is connected with the cover 12 by a line 17 so that the brush can not be 55 withdrawn from the case 10 beyond the position shown in Fig. 3.

An operating rod 18 is pivotally connected with the brush head 14 by means of the staple 19 and has its inner end portion 60 20 hook-shaped as shown in Fig. 3 so that when the brush is drawn out of the case, the rod may be turned back against the case and grasped by the fingers so that the brush will be prevented from slipping back into 65 the case when used. After the brush has been used, the rod is raised and the brush can then be moved into the case and the cover 11 put in place. The brush can then be put in the pocket and conveniently carried without any danger of the bristles becoming bent out of shape or of the bristles 70 being soiled by dust in the pocket. When the bristles become worn so that a new brush is necessary, the new brush can be obtained 75 and the cover 12 removed from the case 10 so that the brush can be drawn out of the case and thrown away. A new line such as a piece of heavy cotton or light string is then connected with the new brush and after 80 the new brush has been inserted into the case, the line is connected with the cover 12 and the cover put in place upon the case. I have therefore provided a brush which can be conveniently carried in the pocket of the 85 user and which is so constructed that the rod which is used for withdrawing and inserting the brush can also be used for holding the brush in an extended position.

What is claimed is:

1. A device of the character described comprising a case open at both ends, a closure for one end of said case removably mounted thereon, a brush slidably mounted in said case, means connecting said brush with said cover to limit the outward movement of said brush, a rod pivotally connected with the head of said brush for moving said brush into and out of said case, said rod being bent at a point adjacent its 95 inner end whereby the rod may be folded back against said case to hold the brush in 100

an extended position, and a closure for the opposite end of said case from said first-mentioned closure.

2. A device of the character described comprising a casing, a cleaning element slidably mounted in said casing, means carried by said casing and connected with said cleaning element for limiting the outward movement of the cleaning element, and

means for moving said cleaning element into 10 and out of said casing and for holding the same in an extended position.

In testimony whereof I affix my signature in presence of two witnesses.

WM. B. DENNIS.

Witnesses:

JOHN A. WOLFE,
JAMES W. JONES.
